UNITED STATES PATENT OFFICE.

EDWARD A. HINTON, OF LIBERTY, MISSISSIPPI.

COMBINED SIDE HARROW AND CULTIVATOR.

Application filed June 15, 1920. Serial No. 389,083.

To all whom it may concern:

Be it known that I, EDWARD ALFORD HINTON, a citizen of the United States, residing at Liberty, in the county of Amite and State 5 of Mississippi, have invented a new and useful Combined Side Harrow and Cultivator, of which the following is a specification.

My invention relates to combined harrows and cultivators, especially useful where inequalities of the soil render existing harrows and cultivator inefficient; and the objects of my invention are, first, to provide a structure capable of working contiguous soil located at different altitudes efficiently; second, to provide for easy, manual operation of the structure; third, to provide for economical construction of the device; fourth, to insure ready replacement of worn, unserviceable parts; and, fifth, to attain these ends 20 with structural simplicity and economy.

I accomplish these aims by the mechanism illustrated in the accompanying drawings, wherein:

Figure 1 represents a side elevation of the 25 structure embodying my invention.

Figure 2 is a bottom plan view thereof.

Figure 3 is a top plan view thereof.

Figure 4 is a rear elevation thereof.

Figure 5 shows the bottom and side views 30 of plate 4.

Figure 6 shows the bed plate, with angular slot, permitting oscillations of the mechanism.

The same designations indicate corresponding parts in all the views.

The cultivator 1 consists of a draft pole 3, having guide handles 2 sustained by brace rod 21 and counterpart stays 22. The plate 23, secured to the upper surface of the beam 40 3, is perforated to pass a screw 13, held in place by wing nut 14, which also penetrates the beam 3 and the plates 4 and 5 attached to the under surface thereof. The plate 4 has a hole 26 to pass screw 13 and two pro-

45 jections or lugs 17. The plate 5, located below plate 4, has a central angular slot 15 which receives the lower terminal of the screw 13; it also has arms perforated by holes 20; it also has two left hand recesses 50 16 and two right hand recesses 17' wherein the projections 17 alternately rest, according as the screw 13 is one leg of the angular slot 15 or the other. Counterpart pivoted frames 7, holding rigidly two series of teeth

6, are secured on one side to the under surface of the plate 5 by pivots 8, so that the two frames can assume different relative positions to the plate 5, and be locked in each position by alternately securing the hooked end of the connecting rod 11 in the holes 10 55 of plate 9 on the under surface of the beam 3, or in the holes 20 of the arms of plate 5. The connecting rod 11, having turnbuckle 25, is pivotally secured by nut 12 to the frame 7 from which the teeth depend. The stirrup-shaped frame 19 is united to the under surface of the frame bars 7 by screws 24, passing holes in the inner terminals of the frames 7, wherein struts 18 are pivotally secured, aiding the reciprocating movements 60 of the frames 7.

It will be perceived that the structure above described and illustrated enables the combined harrow and cultivator to adapt itself automatically to inequalities in the 75 ground being worked, by the ability of the teeth frames to oscillate correspondingly, as permitted not only by the pivotal joinder of the teeth to the draft beam, but also by the slotted plate 5 which allows reciprocations of 70 the threaded screw 13.

The operation of my device is as follows: When it is desired to cultivate a narrow strip of ground, owing to irregularities and undulations of the soil, the hooked ends of the 85 rods 11 are inserted in holes 10 of plate 9, the turnbuckle 25 permitting a rigid joinder. When a wide strip of earth is to be cultivated the ends of rods 11 are withdrawn from holes 10, and, the hooked ends are inserted in perforations 20 in the arms of plate 5; the angular slot 15 in the same plate permitting the altered juxtaposition of parts. The bars 7, holding the teeth, being pivotally joined to the plate 5, enable the teeth alternately to cover a wide and narrow strip of earth, according to the exigencies of the situation.

Having thus fully described my improvements, what I claim is:

The combined side harrow and cultivator herein shown and described, consisting of a perforated plate attached to the upper surface of the draft beam; a screw passing therethrough secured removably by a wing 105 nut; a plate attached to the under surface of the beam, perforated to pass said screw, and having depending projections engaging al-

ternately two series of recesses in a plate thereunder, which also has an angular slot in which the screw reciprocates; and arms 5 perforated to receive the hooked ends of the connecting rods joining the teeth frames thereto; the teeth frames capable of expansion and contraction, enabling cultivation of

strips of ground of variable width; and the adjustable connecting rods whereby the alterability of the teeth frames is effected, 10 for the purposes herein fully shown and described.

EDWARD A. HINTON.
